 (Continued)*Primary Examiner* — John Windmuller*Assistant Examiner* — Steven Czyz(74) *Attorney, Agent, or Firm* — Karen B. Tripp(57) **CLAIM**

I claim the ornamental design for a multi-needle threader, as shown and described.

DESCRIPTION

FIG. 1 is a front perspective view of multi-needle threader of my new design.

FIG. 2 is another front perspective view of the multi-needle threader shown with environment.

FIG. 3 is a front view of the multi-needle threader.

FIG. 4 is a rear view thereof.

FIG. 5 is a left side view, with the right side being a mirror image thereof.

FIG. 6 is a top view thereof; and,

FIG. 7 is a bottom view thereof.

The broken lines depict environment that forms no part of the claimed design.
